LOOM REED

Arno Hornig, Pawtucket, R. I., assignor to Ex-celsior Loom Reed Works, Inc., Pawtucket, R. I., a corporation of Rhode Island

Application September 25, 1939, Serial No. 296,488

3 Claims. (Cl. 139—192)

This invention relates to improvements in loom reeds.

The primary object of this invention is to provide a loom reed constructed entirely of metal, the outer side bars of which are notched for allowing the circulation of solder to all points of contact to the dents, coil spring and side bars to prevent corrosion and rust with the resultant breaking or weakening of the dent wires. 5 A still further object of this invention is to provide a loom reed which will not be subjected to high temperatures during manufacture which has been found to be disadvantageous in that it causes weakening of the dent wires by distempering. 10

Other objects and advantages of the invention will become apparent during the course of the following description of the accompanying drawing wherein,

20 Figure 1 is a side elevational view of the loom reed embodying this invention;

Figure 2 is an end elevational view of the same;

Figure 3 is a top plan view;

25 Figure 4 is an enlarged side elevational view showing the manner of securing the dents in spaced relation;

Figure 5 is an enlarged end elevational view showing the manner in which the dents are anchored in place between side supporting strips; 30 and

35 Figure 6 is an exploded perspective view of the dent wires construction, showing the manner in which the same are positioned between the notched side rails.

In the drawing, wherein for the purpose of illustrating the invention and wherein like reference characters will be employed to designate like parts throughout the same, the reference character 10 will generally be employed to designate a loom reed constructed in accordance with this invention.

The reed 10 comprises a series of parallel spaced dents 11 adapted to receive supporting bars 13 having curved outer surfaces 14 and flattened inner surfaces 15. In construction, the reed dents 11 are inserted between the side bars 13 and are held in spaced relation by the convolutions of a wire 16 wound around the curved surfaces 14 of the spacing bars 13 as clearly shown in Figures 4 and 5. In this manner the dents 11 are held in equi-distant relation and the free ends of the spacing bars 13 are secured to end frame members 17 and 18.

55 After the end portions of the dents 11 which ex-

tend beyond the side frame bars 13 have been anchored together by a suitable molten metal such as solder or the like, side frame bars 19 are placed on opposite sides thereof and extend from the outer edge of each frame member 17 and 18 5 to cover the exposed end portions of the dents.

Each of the side frame bars 19 is notched along one edge as at 20 so that the pointed portions of the notches as at 21 engage or are presented to the side spacing bars 13 adjacent the 10 convolutions of the spacing coil 16. In this manner, air and oil may escape from notches or side bars 19 to allow free flowing of solder to find its way into the crevices of the coil 16 and side bars 19 to prevent acid pockets which cause corrosion 15 and rust thereof causing dent breakage.

It will be understood that the form of the invention herein shown and described is to be taken as a preferred embodiment of the same and that various changes in the shape, size of notches on 20 bars 19 may be resorted to without departing from the spirit of the invention or the scope of the subjoined claims.

I claim:

1. A loom reed, comprising a series of dents, 25 a rectangular frame for holding the dents in position, means adjacent the ends of the dents for holding them in spaced relation and side rails for confining the exposed ends of the dents having edges engaged with the dent spacing means 30 with said engaged edges having notches for allowing the circulation of air, oil and solder to prevent corrosion along the points of contact of the dents with the rectangular frame.

2. A loom reed, comprising a series of dents, 35 side bars extending transversely of the dents adjacent the ends thereof, a spacing coil wound around the side bars and extending between the dents and side frame rails having corresponding edges substantially juxtaposed to said coil with 40 said juxtaposed edges crenelated to allow the circulation of air, oil and solder to prevent corrosion along the points of contact of the dents with the frame of the reed.

3. A loom reed, comprising a series of dents, 45 side bars extending transversely of the reed dents, a spacing coil surrounding the side bars having the convolutions passing between the reed dents and side rail frame bars secured to opposite sides of the reed confining the exposed 50 ends of the dents and substantially contacting the coil, the contacting edges having notches for allowing the circulation of air, oil and solder to prevent corrosion of the dents.
